US00D702913S

(12) **United States Design Patent**
Budde et al.

(10) **Patent No.:** **US D702,913 S**
(45) **Date of Patent:** **** Apr. 15, 2014**

(54) **FINANCIAL TRANSACTION MACHINE**

(75) Inventors: **William Budde**, Dublin, OH (US); **Giancarlo Miranda**, Columbus, OH (US); **Joseph Bradley Nolan**, New Albany, OH (US); **Katherine Dill**, San Francisco, CA (US); **Alison Maiorano**, San Francisco, CA (US); **William Koehler**, San Francisco, CA (US); **Anthony Meredith**, San Francisco, CA (US); **Jonathan Rowell**, San Francisco, CA (US); **Howard Nuk**, San Francisco, CA (US); **David Scott**, Belmont, CA (US); **Tanya Khakbaz**, San Francisco, CA (US); **Charles Ambler**, San Francisco, CA (US); **Hanna Wickholm**, San Francisco, CA (US)

(73) Assignee: **JPMorgan Chase Bank, N.A.**, New York, NY (US)

(**) Term: **14 Years**

(21) Appl. No.: **29/432,411**

(22) Filed: **Sep. 14, 2012**

(51) LOC (10) Cl. **20-01**
(52) U.S. Cl. **D99/28**

(57) **CLAIM**

We claim the ornamental design for a financial transaction machine, as shown and described.

DESCRIPTION

FIG. 1 is a front perspective view of a financial transaction machine showing our new design;

FIG. 2 is a front elevational view of FIG. 1;

FIG. 3 is a back elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1; and,

FIG. 8 is a rear perspective view of FIG. 1.

The broken lines in the drawings illustrate environmental structure on the article and form no part of the claimed design.

1 Claim, 6 Drawing Sheets
